(57) **CLAIM**

The ornamental design for a “writing instrument,” as shown and described.

DESCRIPTION

FIG. 1 is a right side view showing our new design; the left side view being a mirror image thereof;

FIG. 2 is a front view of the writing instrument of FIG. 1; FIG. 3 is a rear view of the writing instrument of FIG. 1; FIG. 4 is a bottom view of the writing instrument of FIG. 1; FIG. 5 is a top view of the writing instrument of FIG. 1; FIG. 6 is a right side exploded view of the writing instrument of FIG. 1, the cap being removed exposing the writing tip; the left side view being a mirror image thereof;

FIG. 7 is a right side view showing a second embodiment of the writing instrument of FIG. 1, the cap being removed and placed on the end opposite of the writing tip; the left side view being a mirror image thereof;

FIG. 8 is a front view of the writing instrument of FIG. 7; FIG. 9 is a rear view of the writing instrument of FIG. 7; FIG. 10 is a bottom view of the writing instrument of FIG. 7; and,

FIG. 11 is a top view of the writing instrument of FIG. 7.
